GLYCINE-STABILIZED ALUMINUM HYDROXIDE-MAGNESIUM COMPOUND CODRIED GEL ANTACIDS AND PROCESS OF MAKING THE SAME

Stewart M. Beekman, Chatham, N.J., assignor, by mesne assignments, to Armour Pharmaceutical Company, Chicago, Ill., a corporation of Delaware

Filed June 6, 1963, Ser. No. 286,074
14 Claims. (Cl. 167—55)

This invention relates to antacid compositions, and, more particularly, to antacid compositions comprising aluminum hydroxide and magnesium carbonate, hydroxide or silicate, mixed as wet gels and codried, and stabilized by the addition of glycine, and to a process of preparing the same.

Antacid preparations are now quite generally employed for the treatment of peptic ulcers, gastric hyperacidity and dyspepsia. Gwilt, Livingstone and Robertson in the Journal of Pharmacy and Pharmacology, X, No. 12,770-775 (1958), describe the characteristics of an ideal antacid. They point out that it should show its maximum neutralizing effect in the shortest possible time, that it should neutralize an adequate amount of gastric hydrochloric acid and maintain its action during the normal period of gastric digestion, that any excess however great beyond the amount required to neutralize free gastric acid should not cause alkalinization, that it should raise the pH of the gastric contents to a level at which pepsin activity is reduced significantly but not totally inhibited, that adequate and repeated doses should be palatable to the hyperacid patient, and that its use should not lead to laxative, constipating or other side effects such as gastric irritation. In addition to these factors the antacid composition should be inexpensive and it should not deteriorate significantly in any respect on aging. These workers summarize the various statements in the literature as to the pH ranges desirable for the ideal antacid, and conclude that a pH within the range from about 3.5 to about 4.5 is apparently the optimum to ensure adequate relief from hyperacidity, particularly if an ulcer site is present, and at the same time permits sufficient residual pepsin activity to avoid secondary digestive disturbances.

Edwards in The Chemist and Druggist, Dec. 14, 1957, page 647, also discusses the properties of an ideal antacid, and suggests that the nearest approach to the ideal attained as of that date was wet activated alumina gel. Dr. Edwards' views of the properties of the ideal antacid are in substantial agreement with those expressed by Gwilt et al.

Liquid aluminum hydroxide gel closely approaches the ideal for an antacid but its liquid form makes it inconvenient to use, especially in the case of ambulatory patients. The liquid gel is quite rapid in its action and gives a prolonged antacid effect in the optimum pH range. It is not significantly affected in its antacid properties by pepsin and it also does not significantly lose its antacid characteristics in aging. However, as Edwards and others have pointed out, it may have a mildly constipating effect which many have sought to remedy by combining it with other ingredients such as magnesium hydroxide or carbonate.

The advantages of the dried gel are obvious. However, the obvious material, dried aluminum hydroxide gel, is actually far from an ideal antacid. It exhibits a lag in its rate of reaction with stomach acids. It does not give a prolonged antacid in the optimum pH range and its antacid properties are severely affected by pepsin. Also, its antacid activity is less than that of the liquid gel, being decreased by the drying and the reduced activity decreases further with aging. These disadvantages have been noted by Gwilt et al. and other workers in this field.

Rossett and Flexner, Ann. Internal Med. 21 119 (1944) reported that mixtures of milk of magnesia (magnesium hydroxide) with aluminum hydroxide gel were more

2

effective gastric antacids than aluminum hydroxide alone. These conclusions were based on *in vivo* experiments on humans, together with extensive clinical experience. Rossett and Rice, Gastroenterology, 26 490 (1954), Morrison, Am. J. Gastroenterology, 21 301 (1954), and Jankelson, Am. J. Dig. Dis., 14 11 (1947) reported that liquid aluminum magnesium hydroxide gels were effective for the treatment of peptic ulcer, hyperacidity, heartburn, spasticity and gastritis. However, simple mixtures of aluminum hydroxide and magnesium hydroxide dried gels have the disadvantage that they result in a high undesirable initial rise in pH, and they also show a rapid diminution in antacid activity on aging. This property is characteristic also of aluminum hydroxide dried gels.

5 In accordance with the invention, there is provided an antacid composition composed of a codried mixture of aluminum hydroxide and a magnesium compound selected from the group consisting of magnesium carbonate, magnesium hydroxide, and magnesium trisilicate, together with a proportion of glycine. Such compositions have a more prolonged antacid activity in the optimum pH range of from 3 to 5 than corresponding dry blends containing the same basic components in the same proportions, and they do not display a high undesirable initial rise in pH. Furthermore, the compositions of the invention are relatively stable, and retain a very high antacid activity on aging, even after two years of storage.

The aluminum hydroxide-magnesium compound codried gels in accordance with the invention approach the theoretical requirements for an ideal antacid in dried form, because they are capable of rapidly increasing the pH of gastric juice to within the optimum pH range of from 3 to 5, and maintain the pH within the optimum range for very long periods of time, of the order of two hours and more. They do not display the initial high pH rise characteristic of the magnesium components. They are non-systemic, and do not upset the acid-base balance of the blood. They are not adversely affected by pepsin in antacid action. They are non-irritating to the gastrointestinal tract. They have a desirable, mild astringent effect, with a minimal constipating or laxative effect. They are palatable, with very little chalkiness, and rehydrate and swell in water to provide a gelatinous, positively charged protective coating for inflamed membranes. 45 Furthermore, they can be prepared at moderate cost, because of the process of their preparation.

The proportions of aluminum hydroxide and magnesium compound in the codried gel are quite critical in developing and maintaining a fast antacid action within the pH range of from 3 to 5. The molecular ratio is expressed herein, for simplicity, as the atomic ratio Al:Mg, and this should be within the range from 2:1 to 0.25:1. Proportions of aluminum hydroxide to give an Al:Mg ratio in excess of 2:1 can be used, without the disadvantageously affecting pH, but with the detriment that the composition is greatly slowed in its antacid action, so that the desired pH is not reached until a considerable time following administration, which is undesirable. The proportion of magnesium compound can exceed the Al:Mg ratio of 0.25:1, but when it does, the maximum pH following administration of the composition may rise to considerably in excess of 5, which is undesirable. Thus, the stated range represents the optimum proportions of the essential ingredients for effective and prompt antacid action.

65 The magnesium component can be a mixture of two or three of magnesium hydroxide, magnesium carbonate and magnesium trisilicate in any proportions. However, the total magnesium content is within the above-stated Al:Mg ratio range.

70 The composition can be prepared in any of several ways. The only prerequisite is that the aluminum hydroxide or aluminum hydroxy carbonate and magnesium carbonate,

hydroxide or trisilicate be in hydrous, gelatinous form at the time of mixing. The components must not have been dried prior to use, i.e., they must contain a sufficient amount of the original gel water to make them moist, usually at least 5%. Any available aluminum hydroxide gels can be used, but the preferred gel is a highly reactive, freshly precipitated aluminum hydroxide containing some carbonate. Any of the available magnesium carbonates, hydroxides and trisilicates can be used, provided they are in moist gel form. A preferred magnesium hydroxide gel is a 30% magnesium hydroxide paste obtained by controlled precipitation from pure aqueous solutions of magnesium sulfate and sodium hydroxide followed by filtration, washing and mixing the washed hydrogel.

Usually, it will be convenient to employ a separately precipitated aluminum hydroxide and magnesium compound, but the magnesium compound may also be co-precipitated with the aluminum hydroxide or aluminum hydroxy carbonate from a common reaction solution, containing hydroxyl, carbonate, silicate, magnesium and aluminum ions, as required for the desired magnesium compound, such as a mixture of sodium hydroxide, magnesium sulfate, and aluminum sulfate, in the case of an aluminum hydroxide-magnesium hydroxide cogel.

The combined precipitates are filtered, and washed free of soluble salts. The mixed hydrous gels are then preferably subjected to a highly intensive shear at room temperature, and then reduced to finely divided powder form, such as by spray drying at a temperature below that at which the gels are adversely affected, or by low temperature air-drying, together with fine pulverizing. The glycine is added to the mixed gels before milling or shearing.

Glycine can be added to the hydrous gels in solid form, preferably finely pulverized, or in the form of an aqueous solution, and thoroughly mixed therewith to ensure uniform distribution throughout the composition. The amount of glycine is not critical, but enough is used to give the desired effect on stability and pH. The amount can be within the range from 2 to 200%, preferably within the range from 15 to 35%, by weight of the hydrous gels, calculated without the water content so as to correspond to the final codried composition weight.

The final composition of the invention is in the form of a codried gel which in finely divided or powdered form is generally soft, white, smooth, tasteless and odorless, and which reacts readily with gastric strength acid contain-

15

The method of Holbert, Noble and Grote, J. Am. Pharm. Assn. 36 149 (1947), 37 292 (1948), Murphey, ibid. 41 361 (1952) uses a test sample of antacid added to 150 ml. of pH 1.5 hydrochloric acid containing 2 g. of pepsin N.F. per liter (artificial gastric juice) at 37.5° C. 20 ml. of the artificial gastric juice is withdrawn every ten minutes and replaced with an equal volume of fresh gastric juice. The modified test procedure used in the work reported in this and the following examples, however, was carried out by continuously introducing fresh artificial gastric juice and removing the antacid-gastric juice mixture by overflow at the rate of 2 ml. per minute. The antacid effect is determined by measuring the pH of the artificial gastric juice during the test period, which is until the pH drops below 2.5.

35
40
45

The method of Bachrach used was as reported by Hinkel, Fisher and Tainter, J. Am. Pharm. Assn., 48 380 (1959). This method consists essentially of adding dilute hydrochloric acid to the antacid at 37.5° C. at such a rate as to maintain a pH of 3.5. This method gives a direct estimate of the speed of action and total available activity, whereas the Holbert, Noble and Grote test procedure demonstrates primarily the buffering effect, as measured by pH and duration of action. In the test procedure as used in this work, the acid used was 0.0875 N hydrochloric acid, containing 2 grams of sodium chloride per liter.

EXAMPLES 1 TO 3

A series of six codried gel antacids, three controls (A, B and C) and three in accordance with the invention (Examples 1, 2 and 3) was prepared in accordance with the following procedure. Highly reactive aluminum hydroxide U.S.P. and pure gelatinous magnesium hydroxide N.F. were separately precipitated to form slurries. The slurries were combined in the proportions given in Table I, filtered, and washed free of soluble salts. The mixed hydrous gels were then subjected to highly intensive shear at room temperature, and reduced to finely-divided powder form by spray-drying. Glycine N.F. (200 mg. per gram of final powder weight) was added to three of these compositions at the time the slurries were combined. The resulting codried gels were then analyzed for aluminum oxide and magnesium oxide, and the atomic ratio Al:Mg determined from the data obtained. The acid-consuming capacity of each antacid composition was determined, and is given in Table I.

TABLE I

¹ Al(OH)₃ U.S.P. calculated as 51% Al₂O₃.

ing pepsin. The pH of aqueous suspensions of the stabilized gels in accordance with the invention is from about 9 to about 9.6 when aluminum hydroxy carbonate is used as the source of aluminum hydroxide. The carbonate content of the final mixture will be within the range from about 5 to about 12%, dependent principally upon the method of drying. The spray-dried samples have spherically shaped particles and are free-flowing. The tray-dried and drum-dried compositions tend to be lumpy or flaky, but can be reduced to a powder by pulverizing.

The following examples, in the opinion of the inventor, represent the best embodiments of the invention.

The antacid characteristics were determined by two methods.

65
70
75

Rock salt infra red spectra (2 to 16 microns) were run on Control A and Example No. 1, the aluminum hydroxide dried gel U.S.P. used as the starting material, the magnesium hydroxide gel N.F. used as the starting material, and crystalline glycine. Nujol and hexachlorobutadiene mulls were made, and samples run at capillary thicknesses vs. air.

The infra red spectra showed that both Control A and Example 1 were simple mixtures.

Antacid activity of the various gels was determined using the Holbert, Noble and Grote procedure, as described above, and the samples were evaluated on the basis of one and two gram dosage levels. The results for the three gel pairs, A and 1, B and 2, and C and 3, are given in Table II.

The Table II data, for Examples 1 to 3, is plotted in FIGURES 1 to 3, and the data for the three codried gels A to C is plotted in FIGURES 4 to 6. In each figure, for purpose of comparison, the comparative data of simple dry blends of the same composition are given.

It is apparent from the data in Table II and in the figures that the codried gels of the invention with glycine (Examples 1 to 3) are in every case superior to the codried gels without glycine (Controls A to C), as well as to the dry blends with and without glycine (Controls D to I). This is so despite the fact that Examples 1 to 3 had only 80% of the antacid content of Controls A to C. The initial rise is considerably lower, and the period of time within which the pH remains within the optimum range above 3 and below 5 is correspondingly extended.

In each case, the codried gels containing glycine did not initially give a pH increase to beyond the permissible limit of 5, and the period during which the pH remained above 3 was extended to as much as 3½ hours.

To determine the effect of aging on the codried gels, they were stored in glass containers which were kept closed at ambient temperatures for five months. The antacid activity of one gram samples was then determined by the Holbert, Noble and Grote test method and compared with values obtained on freshly prepared samples. The results are shown in Table III.

It is apparent from the data in Table III that whereas the gels which did not contain glycine showed a loss of activity of from 20 to 30% after five months' storage, the antacids in accordance with the invention, containing glycine, showed a loss in activity of only 4 to 6%. This comparison is with codried gels. When the dry blend is employed, the improvement in accordance with the invention is even more favorable. In this case, the addition of glycine has practically no effect.

TABLE III

Age of sample, months	A		B		C		D		Increase in activity of item B over item D, percent	
	Antacid activity, time in minutes, H.N. & G. test		Loss in activity after 5 months percent		Antacid activity of corresponding dry blend, time in min., H.N. & G. test					
	0	5

Time above pH 3.0, min.	101	133	83	140	103	140
Time above pH 2.5, min.	118	150	98	158	116	158

The improvement in stability is evident from this data. Whereas Control A was capable of maintaining the pH above 3 only for approximately 100 minutes, Example 1 could maintain the pH above 3 for more than $\frac{1}{2}$ hour longer. Similarly, Control B could maintain the pH above 3 only for approximately an hour and a half, whereas Example 2 was capable of maintaining the pH above 3 for 2 hours and 25 minutes. Control C could maintain the pH above 3 only for somewhat over 100 minutes, whereas Example 3 could maintain the pH at 3 for 2 hours and 20 minutes.

A second series of comparative antacid activity tests was carried out on Controls A to C and Examples 1 to 3, employing the method of Bachrach on 2 gram samples. The test data is given in Table V, on the basis of 1 g. active antacid.

TABLE V

Time (minutes)	Amount of acid added (ml.)					
	Control A		Control B		Control C	
	2:1	1:1	0.5:1	2:1	1:1	0.5:1
0	0	0	0	0	0	0
5	91	143	182	263	154	37
10	140	215	274	304	265	311
15	182	231	212	315	306	335
20	217	225	283	320	311	345
25	227	292	283	320	336	349
30	237	302	283	320	340	351
40	240	306	283	320	344	353
50	241	308	283	320	346	355
60	242	310	283	320	348	356

It is apparent from the data of this test that the acid consuming capacity, the total available activity and the speed of action are considerably greater for the compositions of the invention, Examples 1 to 3, as compared to the codried control gels without glycine. The total acid consumed per hour is 12% to 37% greater.

The in vitro antacid evaluation test by the modified Holbert, Noble and Grote test after 14 months of aging gave the following results:

Maximum pH	4.6
Time to pH 3.0, seconds	5
Time above pH 3.0, minutes	134
Time above pH 2.5, do	150

EXAMPLE 5

Aluminum hydroxide-magnesium hydroxide-magnesium trisilicate glycine codried gel containing equal weights of aluminum hydroxide U.S.P. dried gel (51% Al_2O_3), magnesium hydroxide N.F. (98% $Mg(OH)_2$), magnesium trisilicate U.S.P. (22% MgO) and 20% glycine

136.0 pounds of aluminum hydroxide compressed gel Reheis Type F-1000 containing 10.0% Al_2O_3 , 84.5 pounds of magnesium hydroxide gel (31% $Mg(OH)_2$), 26.7 pounds magnesium trisilicate U.S.P. powder (super bulky grade), 19.3 pounds of glycine and 4.00 pounds of water were mixed for one hour in a Hamilton double motion 150 gallon stainless steel kettle. The slurry was pumped to a second tank and agitated with a high shear mixer for an additional 15 minutes. The resulting homogeneous gel containing 159% product solids was spray-dried in a Bowen 7 foot dryer using a feed rate of 15.5 pounds per minute, a 7" CSE atomizer at 21000 r.p.m., inlet temperature of 750° F. and outlet temperature of 275° F.

The finely-divided white powder retained only 1% on a 45 micron screen. The analysis showed that it contained 13.5% Al_2O_3 , 24% MgO , 13.3% SiO_2 , 5.8% CO_2 . The acid consuming capacity was 197 ml. 0.1 N HCl per gram, which is close to the theoretical value of 199. The Al:Mg atomic ratio was 0.28:1.00.

The antacid properties were determined by the in vitro method of Holbert, Noble and Grote on the basis of 1.0 gram sample. The results are as follows:

TABLE VIII

Time, (minutes):	pH
0	1.5
1	3.9
2	3.9
5	4.0
10	4.1
20	4.2
30	4.2
40	4.1
50	4.1
60	4.0
70	3.9
80	3.9
90	3.6
100	3.4
110	3.1
120	2.8
Time to pH 3.0, sec.	28
Time above pH 3.0	112
Time above pH 2.5	130

The Bachrach method was also used to determine the speed of reaction and total antacid activity. The following data shows the number of milliliters of 0.0875 N HCl per 1.0 gram active ingredient as a function of time.

TABLE IX

Time, (minutes):	Vol., 0.0875 N HCl, ml.
0	0
5	105
10	159
15	214
20	254
25	268
30	271
40	273
50	273
60	273

As previously indicated, the compositions in accordance with the invention are useful in the treatment of internal conditions where excess acidity is to be encountered, such as gastric acidity in the stomach, in, for

example, the treatment of gastric and peptic ulcers. For this purpose, the dry compositions are readily administered in the form of slurries, or as dry powders or tablets, with an excipient, if desired, which are suitably taken orally or added to a liquid carrier such as water.

It is usually most convenient to prepare the compositions in tablet form, and since the compositions are relatively inert and store well, tablets are easily prepared by conventional procedures. The composition can be 5 tabletted as such, or with an excipient mixture of conventional type. The following is a typical tablet formulation:

Antacid composition	grams	32000
Lactose	do	62620
Starch	do	6800
Monosodium phosphate	do	1130
Stearic acid	do	1130

10 The quantity indicated is sufficient to prepare approximately 48,000 tablets, containing 10 grains each of the antacid composition.

The following is claimed:

1. An antacid composition capable as determined by 25 the modified Holbert, Noble and Grote test method of maintaining the pH of artificial gastric juice within the range from about 3 to about 5 for at least one hour, comprising the codried combination of a hydrous gelatinous aluminum hydroxide material selected from the group

30 consisting of aluminum hydroxide and aluminum hydroxy carbonate and a gelatinous magnesium compound selected from the group consisting of magnesium carbonate, magnesium hydroxide and magnesium trisilicate in an atomic ratio Al:Mg within the range from about 2:1 to about 0.25:1, and from 2 to 200% by weight of the hydrous gels, calculated sans water, of glycine to increase the stability of the composition to aging.

2. An antacid composition in accordance with claim 1 35 in which the aluminum hydroxide is a hydrous gelatinous aluminum hydroxy carbonate.

3. An antacid composition in accordance with claim 1 40 in which the gelatinous magnesium compound is magnesium hydroxide.

4. An antacid composition in accordance with claim 1 45 in which the gelatinous magnesium compound is magnesium carbonate.

5. An antacid composition in accordance with claim 1 50 in which the gelatinous magnesium compound is magnesium trisilicate.

6. An antacid tablet comprising a composition in accordance with claim 1 and an excipient.

7. A process for preparing an antacid composition 55 capable as determined by the modified Holbert, Noble and Grote test method of maintaining the pH of artificial gastric juice within the range from about 3 to about 5 for at least one hour, which comprises mixing a moist hydrous gelatinous aluminum material selected from the group consisting of aluminum hydroxide and aluminum hydroxy carbonate and a moist gelatinous magnesium compound selected from the group consisting of magnesium carbonate, magnesium hydroxide and magnesium trisilicate in an atomic ratio Al:Mg within the range from about 2:1 to about 0.25:1 and from 2 to 200% by weight of the hydrous gels, calculated sans water, of glycine to increase the stability of the composition to aging, and drying the resulting mixture.

8. A process in accordance with claim 7 in which the aluminum hydroxide gel is an aluminum hydroxy carbonate gel.

9. A process in accordance with claim 7 in which the aluminum hydroxide gel and magnesium hydroxide gel are formed in situ by coprecipitation from a common 75 solution.

11

10. A process in accordance with claim 7 in which the gelatinous magnesium compound is magnesium carbonate.

11. A process in accordance with claim 7 in which the gelatinous magnesium compound is magnesium hydroxide.

12. A process in accordance with claim 7 in which the gelatinous magnesium compound is magnesium trisilicate.

13. An antacid composing according to claim 1 containing, by weight of the hydrous gels and calculated sans water, from 15 to 35 percent glycine. 10

12

14. A process according to claim 7 in which is added, by weight of the hydrous gels and calculated sans water, from 15 to 35 percent glycine.
